LAMP SOCKET

William J. Coyle, Waltham, Mass., assignor to
United-Carr Fastener Corporation, Cambridge,
Mass., a corporation of Massachusetts

Application March 29, 1949, Serial No. 84,047

3 Claims. (Cl. 339—180)

1

This invention relates generally to sockets for electric lamps, and has particular reference to a socket adapted to receive a lamp having a threaded base.

Electrical lamps of this type are commonly provided with a cylindrical base formed of sheet metal, having threads rolled or stamped into the periphery, to enable the base to be screwed into a socket. The base-engaging portion of the socket is also commonly formed of a cylindrical piece of sheet metal, having threads disposed therein to cooperate with the threads on the base.

During mass production manufacture of both the socket and the base, it is impractical to maintain close dimensional tolerances of the sheet members, and consequently the base and socket are subject to small but significant variations in diameter. Such variations are undesirable, since when a slightly undersized base is screwed into a slightly oversized socket, not only is a poor electrical connection obtained, but the base may fit so loosely in the socket that vibration and handling during use will cause the connection to be completely broken. This difficulty is more pronounced with the smaller sizes of lamps, and is particularly objectionable where several lamps are connected in series, in which case loosening of one lamp in its socket will break the connection to all the other lamps.

The object of the invention is to provide a socket having means therein for resiliently engaging a threaded lamp base, in which said engaging means is expandable to accommodate lamp bases having small but appreciable differences in diameter.

A further object of the invention is to provide a socket for engaging a threaded lamp base, in which the socket is provided with resilient thread-engaging means and resilient base-engaging means adapted to force an assembled base into engagement with the thread-engaging means.

A still further object of the invention is to provide a socket for receiving a threaded base, in which the socket is provided with resilient arms adapted to engage the base and the threads thereon.

Other objects of the invention will, in part, be obvious, and will, in part, appear hereinafter. For a fuller understanding of the nature and objects of the invention, reference should be had to the following detailed description, taken in conjunction with the accompanying drawing, in which:

Fig. 1 is a perspective view of the socket in which portion of the socket body is broken away to show the arrangement of the base-engaging member disposed therein;

2

Fig. 2 is a view in elevation, partly in section, of the socket illustrating the means for retaining the base-engaging member in the socket body;

5 Fig. 3 is a view in section taken on line 3—3 of Fig. 2;

Fig. 4 is a view in section taken on line 3—3 of Fig. 2; also showing a section of an inserted lamp base;

10 Fig. 5 is an enlarged view of the lower portion of the base-engaging member, showing details of construction of the center connection; and

Fig. 6 is a view in elevation, partly in section, of the socket and an assembled lamp base.

15 Referring to the drawing, there is illustrated a lamp socket 10, which is adapted to receive and make electrical connection with a lamp 12, of the type which has a sheet metal contact base 14 having socket-engaging threads 16, and a center contact member 18 disposed on the end of the base.

The socket 10 comprises a substantially cylindrical hollow socket body 20 and a base-engaging contact member 22. The socket body 20, which is preferably formed of molded plastic, is provided with a pair of internal shoulders 24, and a base 26 at one end of the body having an internal opening 28 for receiving electrical lead wires 30. The base-engaging contact member 22 comprises a base plate 32 and a pair of base-engaging contact arms 34 and 36 extending upwardly therefrom. The base plate 32 is provided with a central opening 38 having an insulating bushing 40 and a rivet 42 disposed therein, for attaching a center contact member 44. The corners of the base 32 are turned upwardly to form prongs 46 to engage the socket body, and retain the contact member in the socket.

40 The contact arms 34 and 36 are shaped and arranged to be supported laterally by the body 20 when a lamp is assembled therein and are provided with shoulders 47 to rest on the internal body shoulders 24. To allow the threaded base 14 to be screwed into engagement in the socket, the contact arm 34 is provided with a number of thread-engaging prongs 48, vertically spaced to correspond to the pitch of the threads 16 of the base.

In the preferred embodiment, the prongs 48 extend inwardly and then outwardly forming a convex thread-engaging portion 50 and a free end portion 52, which is disposed for support by 45 the socket body 20 when the base is assembled in the socket. The contact arm 36 is provided with a plate 54 having a base-engaging surface 56. In the preferred form, the plate 54 is curved to conform to the shape of the socket body 20, but has 55 a radius of curvature greater than that of the

body, so that the plate contacts the body only at the outer edges. This provides a space 58 between the plate and the body, into which the plate is free to expand during insertion of a lamp base.

The dimensions of the contact member 22 are such that the insertion of the base 14 causes outward flexing of the plate 54, thereby forcing the base into engagement with the prongs 48, and causing a frictional drag between the contact arms and the base, to resist rotation of the base 10 in the socket.

The prongs 48, by virtue of their convex shape, also have a degree of flexibility, to resiliently engage the base 14.

By reason of the resilience of the plate and prongs, the socket is able to accommodate lamp bases which are slightly undersize or oversize, since the flexing of the plate and prongs by insertion of the base insure that the base is firmly held in the socket. The socket may be provided with several contact arms having prongs and plate, however, by provision of only one set of thread-engaging prongs, insertion of the base into the socket is facilitated, since with this arrangement, it is impossible to start the base into the socket cross-threaded.

Since certain obvious modifications may be made in the device without departing from the scope of the invention, it is intended that all matter contained herein be interpreted in an illustrated and not in a limiting sense.

I claim:

1. A socket for electric lamps and similar devices having a threaded-connecting base, the socket comprising: a hollow socket body of insulating material having an outer tubular wall portion with a base receiving opening at one end, an inner tubular wall portion, radially inwardly extending shoulders between said inner and outer tubular wall portion, and an apertured end wall at the opposite end of said inner tubular wall portion, and a substantially U-shaped base engaging member disposed in said body, formed from conducting material and comprising a bight portion and opposed leg portions, said bight portion having pointed prongs, intermediate said leg portions extending angularly in the same general direction as said leg portions in biting engagement with the walls of said inner tubular wall portion to prevent axial withdrawal of said base engaging member from said body, said leg portions includ-

ing shoulder portions in engagement with the inwardly extending shoulders of said body to limit axial movement of said base engaging member upon insertion into said body, one of said leg portions having at its outer free end threaded base engaging fingers extending circumferentially adjacent the walls of said outer tubular portion for engaging such a base between the threads thereof, and the other of said leg portions having at its outer free end a resilient curved plate portion with its side edges in engagement with the walls of said outer tubular wall portion and with the portion thereof intermediate said side edges disposed in spaced relation to the side walls of said outer tubular wall portion on an arc with a radius greater than that of the walls of said outer tubular wall portion to provide resilient means for engaging such a base and urging it into engagement with said thread engaging fingers.

2. A socket in accordance with claim 1 wherein the side edges of the plate portions are tapered inwardly adjacent the shoulder in the leg portion to facilitate insertion of the base engaging member into the body member.

3. A socket in accordance with claim 2 having contact means secured to the bight portion of the base engaging member but insulated therefrom providing a resilient contact member disposed between the leg portions of the base engaging member and having separate connecting wires extending from said bight portion and said contact through the apertured end wall of the body member.
